D32/14.1

FIG. 1 is a front top left perspective view of a shoe disinfecting device.

FIG. 2 is a top view thereof.

FIG. 3 is a bottom view thereof.

FIG. 4 is a left view thereof.

FIG. 5 is a right view thereof.

FIG. 6 is a front view thereof; and,

FIG. 7 is a rear view thereof.

The broken line portions of the figure drawings are included to show portions of the article that form no part of the claimed design.

1 Claim, 7 Drawing Sheets
